(57) **CLAIM**

The ornamental design for vehicle-wheel front face, as shown
and described.

DESCRIPTION

FIG. 1 is a perspective view of a vehicle wheel front face
according to my new design;

FIG. 2 is a front elevational view thereof; and,

FIG. 3 is a side elevational view thereof.

The broken line showing of the front rim, the side of the wheel
and the center cap of the wheel is included for the purpose of
illustrating environment and forms no part of the claimed
design.

1 Claim, 3 Drawing Sheets

FIG. 1

FIG. 2

FIG. 3
